United States Patent Office

Des. 188,555
Patented Aug. 9, 1960

188,555

SAUCE PAN OR THE LIKE

George H. Frost, Ashland, Ohio, assignor to Westinghouse Electric Corporation, a corporation of Pennsylvania

Filed June 22, 1959, Ser. No. 56,439

Term of patent 14 years

(Cl. D44—1)

FIG.4.

FIG.5.

Fig. 1 is a perspective of a sauce pan or the like; Fig. 2 is a side elevation of the knob, on an enlarged scale;

Fig. 3 is an edge elevation thereof;

Fig. 4 is a side elevation of a foot element, on an enlarged scale; and

Fig. 5 is an edge elevation thereof.

The dominant features of this design are shown in full lines.

I claim:

The ornamental design for sauce pan or the like, as shown and described.
